UNITED STATES PATENT OFFICE.

HARRY A. BOWER, OF CHELSEA, MASSACHUSETTS, ASSIGNOR TO WENDELL P. LEE AND WILLIAM H. BREEN, OF BOSTON, MASSACHUSETTS.

HEATING AND ILLUMINATING ATTACHMENT FOR GAS-BURNERS.

SPECIFICATION forming part of Letters Patent No. 609,656, dated August 23, 1898.

Application filed January 4, 1897. Serial No. 617,895. (No model.)

To all whom it may concern:

Be it known that I, HARRY A. BOWER, of Chelsea, in the county of Suffolk and State of Massachusetts, have invented certain new and useful Improvements in Heating and Illuminating Attachments for Gas-Burners, of which the following is a specification.

This invention has for its object to provide an attachment for a gas-burner which will serve two distinct purposes, one of which is to utilize the heat generated by the gas-flame in heating an apartment, and the second of which is to increase the illuminating or light-giving power of the gas.

To these ends my invention consists of an attachment for gas-burners comprising a casing preferably having a large radiating-surface for giving out heat, and a reflector suitably connected with the casing and adapted to reflect the rays of light from the flame downwardly.

It likewise consists of an attachment having those features of improvement which I have shown in the drawings and which I shall hereinafter describe in detail and then point out in the claims hereto appended.

Reference is to be had to the annexed drawings, and to the letters marked thereon, forming a part of this specification, the same letters designating the same parts or features, as the case may be, wherever they occur.

Of the drawings, Figure 1 is a side elevation of a device embodying my invention. Fig. 2 is a vertical section through the same. Fig. 3 is a plan view.

In carrying out my invention I provide a casing having a dome-shaped top a and an inverted frusto-conical portion a' , united by a seam a^2 , and both formed, preferably, of sheet-iron or other good heat-conducting material.

The casing is provided with a series of apertures a^3 , formed in the dome-shaped part thereof, just above the seam a^2 , and it is open at the bottom, as shown in Fig. 2. Within the casing is arranged a ring or band b of any suitable material which will reflect light and which I generally construct of aluminium, as that is cheap and easily to be obtained. It is smaller in diameter than the part a^2 of the casing and is held concentrically therein by

bolts c and nuts c' , so as to leave an annular space d between it and the casing.

Preferably the reflector is frusto-conical in shape, with the upper edge slightly curved inward.

The casing is supported upon a rod e , which is threaded at its lower end to receive a nut e' , upon which the casing rests. The rod e is formed at its upper end into a collar e^2 , so as to be adjustably mounted upon a horizontal arm f , mounted in a clamp g , which may be secured upon the main stem of a gas-bracket by screws j' . The collar e^2 is provided with set-screws e^3 , whereby the rod e may be secured at any point along the rod f .

The clamp g may be in the form shown and may be provided with a series of apertures g^2 to receive a series of arms f , whereby the casing may be suspended over each gas-burner in a chandelier.

The conical cap h is supported by a collar h' on the rod e and extends beyond the edges of the casing for a purpose to be set forth.

Preferably the casing is suspended above the gas-burner, as shown in Figs. 1 and 2, so that the flame will not impinge upon the aluminium band and so that the heated air and products of combustion arising from the gas-flame will pass into the dome a and pass out through the apertures therein.

The products of combustion of the gas and the heated air pass out through the aperture a^3 , so that the draft is maintained at all times. The heat of the flame and of the reflector-band is transmitted to the casing, which has a large exterior surface and which becomes heated to such an extent as to raise the temperature of a relatively large room in a very short time.

By employing the cap h the rays of heat are deflected downwardly and the heat of the casing is prevented from injuring the ceiling or from causing the suspending-rod to become too highly heated. Preferably the cap extends for a short distance beyond the periphery of the casing, and though it is located quite near to the dome-shaped top of the latter at the same time practically no heat is felt above it.

By forming the reflecting-band in such way as to leave an annular space between it and

the casing I provide for the passage of air between them, so as to prevent the casing from becoming too highly heated and to supply a sufficient quantity of air to be heated 5 and discharged through the orifices a^3 .

In addition to the foregoing features I also provide a deflector j in the shape of a cone, with inwardly-projecting fingers j' , which rest upon the burner just below the lava tip k , the 10 deflector being arranged to guard the burner against the heat rays and keep it cool.

Having thus explained the nature of the invention and described a way of constructing and using the same, though without attempting to set forth all of the forms in which 15 it may be made or all of the modes of its use, I declare that what I claim is—

1. A heater and light-reflector, comprising a casing, and a light-reflecting band secured 20 in said casing and being of a smaller cross-

diameter than said casing, whereby there is an annular space between them, and means for permitting the circulation of air through said space.

2. A heater and light-reflector, comprising 25 a dome-shaped casing closed at the upper end and having a series of apertures in its sides, a frusto-conical light-reflecting band, within said casing, and means for securing said band in said casing so as to leave an annular space 30 between them.

In testimony whereof I have signed my name to this specification, in the presence of two subscribing witnesses, this 28th day of December, A. D. 1896.

HARRY A. BOWER.
